(57) **CLAIM**

The ornamental design for a mobile robotic platform with surface pattern, as shown and described.

DESCRIPTION

FIG. 1 is a front perspective view of a mobile robotic platform with surface pattern showing the claimed design in accordance with the present invention;

FIG. 2 is a left side elevational view thereof;

FIG. 3 is a right side elevational view thereof;

FIG. 4 is a rear perspective view thereof;

FIG. 5 is a rear elevational view thereof;

FIG. 6 is a front elevational view thereof;

FIG. 7 is a top plan view thereof; and,

FIG. 8 is an exemplary diagram showing the nature and environment of use for the surface pattern applied to a mobile robotic platform in accordance with the present invention.

As indicated in the title, the design is directed to an ornamental mobile robotic platform with surface pattern, also known as a mobile robot, mobile autonomous robot, robotic carrier or robotic transporter. The stippling in FIGS. 1, 2, 3, 4 and 8 represent a visible light effect or illumination, or glow, which is a part of the claimed design. Broken lines, within the claimed surface pattern design, that depict recesses, gaps and/or protrusions on the surface of the mobile robotic platform in some embodiments, are for illustrative purposes only and form no part of the claimed design. Broken lines representing the mobile robotic platform, a robotic manipulator affixed to the top of the mobile robotic platform and wheels underneath the mobile robotic platform are also for illustrative purposes only and form no part of the claimed design.

1 Claim, 8 Drawing Sheets
